UNITED STATES PATENT OFFICE

RALPH H. CHILTON, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed November 20, 1926. Serial No. 149,771.

This invention relates to cooling units for mechanical refrigerators, and more particularly to cooling units which are adapted to be installed in refrigerating cabinets of the household type. However, it is to be understood that the present invention may be adapted for larger refrigerating cabinets of the commercial type.

The present invention includes among its 10 objects the provision of a cooling unit of simple and economical construction, which will quickly congeal or freeze substances which are placed within a freezing compartment provided by the unit, and which will 15 effectively cool the food compartment of the cabinet.

Further objects and advantages of the present invention will be apparent from the following description, reference being had to the 20 accompanying drawings, wherein a preferred form of the present invention is clearly shown.

In the drawings:

Fig. 1 is a front view of a refrigerator 25 cabinet with the doors open in order to show the food compartment and a cooling unit within a cooling compartment;

Fig. 2 is a view on a larger scale than Fig. 1, showing the front view of the cooling unit 30 which is suspended within the cooling compartment of a cabinet, the walls of which are shown in vertical section; and

Fig. 3 is a side elevation of the cooling unit drawn to the same scale as Fig. 2.

Referring to the drawings, 20 designates 35 a refrigerator cabinet which provides an L-shaped food compartment 21 separated from a cooling compartment 22 by a horizontal partition 23 and a vertical partition 24.

The partition 24 is provided with a flue 25, admitting relatively warm air from the food compartment 21 to the cooling compartment 22; and the partition 23 is provided with a flue 26, admitting cooled air from the compartment 22 to the compartment 21. The partition 23 supports a baffle 27 which prevents moisture dripping from the cooling unit above from entering the flue 26. The baffle 27 45 directs such moisture upon the upper surface

of the partition 23, and this moisture is conducted away through a drain pipe 28.

The cooling unit located within the cooling compartment 22, includes a boiler or header 30 attached to the top wall of the cabinet 55 by bracket members 31 and 32. Condensed refrigerant is conducted to the header 30 from a compressor and condenser (not shown) through a pipe 33 and a fitting 34. Refrigerant is admitted from the fitting 34, 60 as needed, by a float-controlled valve (not shown), of suitable construction, located within the header 30. Expanded refrigerant is conducted back to the compressor through a fitting 35 and a pipe 36. The refrigerating 65 compressor and condenser with which the pipes 33 and 36 are connected, may be located outside of the cabinet, if desired, or may be placed within a machine compartment located below the food compartment 21, said 70 compartment having a removable front wall 37 provided with louvers 38.

The cooling unit includes also a plurality 75 of U-shaped loops 40 and 41, of metal of good thermal conductivity, which are arranged preferably in horizontal rows, both branches 80 of a loop in any row being in the plane of that row. The opposed sets of loops 40 co-operate with the header 30 to provide or enclose a freezing space zone 42 therebetween which 85 may contain one or more metal sleeves 43 which are attached to and thermally connected with each branch of each of the loops 40. By arranging the loops 40 in this manner, a large area of thermal contact between the 90 loops and the sleeves 43 may be afforded. The sleeves 43 may receive metal trays 44 containing matter to be frozen.

This arrangement of loops 40 affords also a large area of thermal contact between these 95 loops and sheet metal thermal conductors 45 each of which is attached to and thermally connected with both branches of the loops 40 in an inner row of loops. The plates 45 serve to isolate the space 42 from warm air currents and to conduct heat from circulating air to the ducts 40 and thereby assist in cooling the circulating air and also limit the accumulation of frost upon the loops 40. Thus the space 42 is isolated from the circulating 100

air by the header 30, loops 40 and plates 45, so that quick freezing may be obtained; and, at the same time the opposed sets of outer loops 41, being provided with the plates 46, 5 are intimately associated with the circulating air. The loops 41, lying outwardly of the freezing zone, provide a cooling zone for pre-cooling the air before it comes in contact with the freezing zone. The freezing zone, being 10 nested within the cooling zone, is protected from the warming action of the circulating air whereby a relatively low temperature can be maintained between the opposed loops 40 while the cooling zone portion cools the 15 circulating air to a desired temperature for general refrigeration within the refrigerator.

The arrangement is such that the outer loops 41 will rapidly defrost during the idle periods of the refrigerant compressor but the 20 freezing space 42, being shielded as above described, will not defrost during such idle periods to any substantial extent. It is therefore obvious that the automatic controls for starting and stopping the refrigerant 25 compressor may be so adjusted that the idle periods of the compressor will be of such duration that the outer loops 41 will nearly or completely defrost at each idle period without at the same time reducing the temperature 30 of the freezing space 42 below the freezing point. By so preventing an accumulation of frost on loops 41 the air cooling efficiency thereof will be substantially increased.

In case it is desired to divert some of the 35 circulating air into the freezing space 42 to give a more rapid cooling of the circulating air at a sacrifice of rapidity of freezing in space 42 the upper portions of the plates 45 may be bent as indicated by dotted lines 45a 40 in Fig. 2.

While the present invention contemplates the use of any suitable ducts for cooling the circulating air, the U-shaped loops 41 may be used advantageously since they, like the 45 loops 40, are so arranged that both branches of each loop may be attached to and thermally connected with a thermal conducting plate, such as one of the plates 46, this arrangement thus providing a relatively large 50 area of contact between the plates 46 and loops 41. The plates 46 serve as thermal conductors or fins to increase the rate of heat transfer between the circulating air and loops 41, and thus assist in cooling the 55 surrounding air more efficiently and produce a greater amount of defrosting of the loops 41 during the idle periods of the refrigerating machine. These plates 46 also tend to stiffen the structure.

60 Preferably, the loops 40 are joined to the header 30 before attaching them to the sleeves 43. The loops 40 may be readily bent laterally of the header so that they may be adjusted to fit snugly the side walls of the 65 sleeves, in order to assist in providing a good

thermal connection between the sleeves and loops 40. After the unit has been inserted in the chamber 22, the loops 41 may easily be bent laterally of the header so that they may be located in the most efficient air cooling 70 position.

While the form of embodiment of the present invention as herein disclosed, constitutes a preferred form, it is to be understood that other forms might be adopted, all coming 75 within the scope of the claims which follow.

What is claimed is as follows:

1. A cooling unit for mechanical refrigerators comprising a header, a plurality of conduits depending from the header, certain of said conduits being U-shaped loops arranged in rows cooperating with the header to enclose a freezing space, the rows being horizontal and containing both branches of certain loops, the other conduits extending 80 downwardly along the loops and being located so as to be substantially entirely subjected to air circulating adjacent the cooling unit.

2. A cooling unit according to claim 1 in which plates are each thermally connected with the loops and serve further to isolate the freezing space from air currents.

3. A cooling unit according to claim 1 in which plates are thermally connected with the portions of the loops more remote from the freezing chamber.

4. A cooling unit according to claim 1 in which ice tray sleeves are supported by and thermally connected with the loops.

5. A cooling unit for mechanical refrigerators comprising an elongated header and a plurality of conduits depending from the header, certain of which co-operate with the header to enclose a freezing space, and certain others being U-shaped loops arranged in downwardly extending rows, each row containing both branches of certain loops, said last mentioned loops being spaced from the freezing space and substantially entirely subjected to air circulating adjacent the cooling unit.

6. A cooling unit according to claim 5, in which the U-shaped loops are arranged in horizontal rows, and in which a plate is 115 thermally connected with the loops in each row.

7. A cooling unit for mechanical refrigerators comprising an elongated header and a plurality of parallel rows of U-shaped loops depending from the header, each row containing both branches of each of certain loops, the inner rows of loops co-operating with the header to enclose a freezing space, and the other rows being substantially entirely exposed to air circulating about the unit.

8. A cooling unit according to claim 7, in which plates are each thermally connected with each row of loops.

9. A cooling unit according to claim 7, in which plates are each thermally connected with each row of loops and in which the plates are each located on the side of the row of loops most remote from the freezing space. 5
10. A cooling unit for mechanical refrigerators adapted to be placed in the path of the medium to be cooled thereby, said cooling unit comprising heat exchange means in intimate contact with a refrigerant and with said medium to be cooled, said heat exchange means having a portion providing a freezing zone and including duct loops each having a plurality of aligned branches arranged in a plane with like branches of the other of said loops, and another portion formed to provide a cooling zone, the material of said second mentioned portion lying outwardly of and along the freezing zone in the path of 15 the circulating medium and so constructed and arranged as to provide a shield of heat exchange material for shielding the freezing zone from the action of the circulating medium. 20
- 25 11. A cooling unit for mechanical refrigerators adapted to be placed in the path of the medium to be cooled thereby, said cooling unit comprising heat exchange means in intimate contact with a refrigerant and with said medium to be cooled, said heat exchange means having a portion constructed and arranged to provide a freezing zone, and another portion formed to provide a cooling zone, said second mentioned portion including a duct loop having a plurality of branches lying outwardly of and along one side of the freezing zone in the path of the circulating medium and so constructed and arranged as to provide a shield of heat exchange material 30 for shielding the freezing zone from the action of the circulating medium. 35
12. A cooling unit for mechanical refrigerators adapted to be placed in the path of the medium to be cooled thereby, said cooling unit comprising heat exchange means in intimate contact with a refrigerant and with said medium to be cooled, said heat exchange means having a portion constructed and arranged to provide a freezing zone, and another portion formed to provide a cooling zone, said second mentioned portion including duct loops, the branches of one of the latter loops lying outwardly of and along one side of the freezing zone and in the path 40 of the circulating medium and the branches of the other of said latter loops lying outwardly of and along another side of the freezing zone in the path of the circulating medium, said latter loops being so constructed and arranged as to provide a shield of heat exchange material for shielding the freezing zone from the action of the circulating medium. 45
- 50 13. A cooling unit for mechanical refrigerators adapted to be placed in the path of the medium to be cooled thereby, said cooling unit comprising heat exchange means in intimate contact with a refrigerant and with said medium to be cooled, said heat exchange means including opposed duct loops each including a plurality of branches cooperating with the branches of the opposed loop to provide a freezing zone, and another conduit portion formed to provide a cooling zone, the material of said second mentioned portion lying outwardly of and along the freezing zone, in the path of the circulating medium and so constructed and arranged as to provide a shield of heat exchange material for shielding the freezing zone from the action of the circulating medium. 55
- 60 14. A cooling unit for mechanical refrigerators adapted to be placed in the path of the medium to be cooled thereby, said cooling unit comprising heat exchange means in intimate contact with a refrigerant and with said medium to be cooled, said heat exchange means including opposed duct loops each including a plurality of branches cooperating with the branches of the opposed loop to provide a freezing zone, and another portion comprising duct loops formed to provide a cooling zone, the material of said second mentioned portion lying outwardly of and along the freezing zone in the path of the circulating medium and so constructed and arranged as to provide a shield of heat exchange material for shielding the freezing zone from the action of the circulating medium. 65
- 70 15. A cooling unit for mechanical refrigerators comprising a horizontally elongated header adapted to contain a quantity of liquid refrigerant, duct means connected with the header and adapted to receive liquid refrigerant from the header, said means being arranged in sets, one set being disposed longitudinally along and on one side of the header and another set being disposed on the opposite side of the header, said latter set including loops each having a plurality of upright branches, the upright branches of a loop being arranged in a row with other upright branches of said set, said latter set cooperating with the first set to provide a refrigerating zone, and fins thermally connected to and extending along the duct means. 75
